UNITED STATES PATENT OFFICE.

MILTON D. ADLER, OF NEW YORK, N. Y.

DESIGN FOR AN ARTICLE OF MANUFACTURE.

56,957.

Specification for Design.

Patented Jan. 25, 1921.

Application filed July 27, 1918. Serial No. 247,054. Term of patent 14 years.

To all whom it may concern:

Be it known that I, MILTON D. ADLER, a citizen of the United States, and resident of the city, county, and State of New York, have invented a new, original, and ornamental Design for an Article of Manufacture, of which the following is a specification, reference being had to the accompanying drawing, forming a part thereof.

In the drawings I have shown a face view of a pennant to which my design is applied, the pennant being indicated in out-

line which, however, is not a part of the design, as I contemplate that the same may also be embodied in or applied to various other articles of manufacture, such as emblems, flags, pillow-tops, or articles of similar nature.

The design includes the words "American Though and Through," as shown.

I claim:—

The ornamental design for an article of manufacture, as shown and described.

MILTON D. ADLER.
